DEVICE FOR DISINFECTING TELEPHONE MOUTHPIECES

Albert Finlayson and William Richard Smith,
Kingston upon Hull, EnglandApplication June 19, 1950, Serial No. 168,878
In Great Britain June 20, 1949

6 Claims. (Cl. 179—185)

1

This invention relates to a device for disinfecting a telephone mouthpiece.

It is common practice to disinfect the mouthpiece of a telephone by wiping the mouthpiece with a cloth impregnated with a disinfectant or by spraying a disinfectant liquid in atomised form over the mouthpiece. Such treatment of the mouthpiece is beneficial but transient and the treatment must be repeated at frequent intervals.

An object of the present invention is to provide a device for disinfecting a telephone mouthpiece which is substantially permanent in character, is relatively cheap to produce and which may be permanently attached to the mouthpiece as an auxiliary component without impairing or in any way interfering with the speech characteristics.

According to the present invention a device for disinfecting a telephone mouthpiece includes a cage adapted to contain disinfectant and to fit snugly on the inside of the mouthpiece and an arm adapted to engage both with the cage and in an aperture in the mouthpiece diaphragm to retain the cage in position. The arm may be permanently attached to the cage.

The cage may have an opening at its rear, the said opening being closed by the mouthpiece itself when the cage is in position on the mouthpiece, or it may be made in two portions; a rear solid portion having guide means at either side and a front perforated portion slidably engaging within said guide means. Alternatively, the front portion may be hingedly connected at one edge to the rear solid portion.

Preferably the arm is in the form of a flat flexible strip of spring steel having a lip at its outer end adapted to engage the front face of the cage to assist in retaining the cage within the mouthpiece. The inner end of the arm may be formed as a pin of circular cross section to fit within one of the apertures provided in the mouthpiece diaphragm. Penetration may be limited by a collar on the pin. The pin may be split longitudinally to retain the arm in its holding position by its own resilience, or alternatively the inner end may be turned down after insertion.

The invention will now be more particularly described by reference to the accompanying drawings in which:

Fig. 1 represents a perspective view of one embodiment of the invention located within a telephone mouthpiece,

Fig. 2 represents a perspective view of the same cage and arm as illustrated in Fig. 1,

2

Fig. 3 represents a part sectional elevation of the cage and arm as illustrated in Fig. 1.

Fig. 4 represents a perspective view of another embodiment of cage and arm,

Fig. 5 represents a part sectional elevation of the cage and arm illustrated in Fig. 4 as fitted into the mouthpiece,

Fig. 6 represents a perspective view of a further embodiment of the invention, and

Fig. 7 represents a perspective view of another embodiment of the invention.

Referring to Figs. 1-3, a cage 11 consists of a perforated rectangular panel 12 which is curved lengthwise so as to present an outwardly facing concave surface. Crescent shaped flanges 13 depend from the longitudinal edges of the panel 12 the curvature of the edge of each dependent flange being greater than that of the panel 12 and conforming substantially with the curvature 15 of the telephone mouthpiece such that when the cage 11 is placed in position within the telephone mouthpiece a space is provided within which disinfectant may be contained. The cage 11 is held in position within the mouthpiece by 20 an arm 14 made from a strip of flexible spring steel of substantially rectangular cross section, which is cranked at 15 to provide a bridge 16 extending across the width of the cage and having a lip 17 which engages with the outer dependent flange 13. At its opposite end, the arm 25 is formed as a pin 18 of circular cross section, the pin terminating in a collar 19 at its inner end. The method of holding the cage within the mouthpiece is shown more particularly in Figs. 30 1 and 3, the hatched section 20 representing disinfectant.

Referring to Figs. 4 and 5, a cage 21 consists of a perforated rectangular panel 22 which is curved lengthwise so as to present an outwardly facing concave surface. A flange 23 extends along one edge of the panel 22 and is shaped to coincide with the lip on the mouthpiece. In this embodiment a straight arm 24 has a circular pin 25 at one end and a lip 26 at its other end. It is made 35 from a flexible steel strip enabling it to hold the cage in position in the mouthpiece as illustrated in Fig. 5. Sufficient space is provided between the panel 22 and the mouthpiece to accommodate disinfectant, either in the form of a thin wafer or as liquid on a cotton wool carrier.

Fig. 6 shows a further embodiment in which a perforated panel 27 has dependent crescent shaped flanges 28 along each longitudinal edge, each flange then being bent outwardly to provide rims 29. A solid rear panel 30 having in-

wardly directed channels 31 slidably engages with the front perforated panel to form a self-contained cage.

Fig. 7 illustrates a further embodiment of a self-contained cage in which the front perforated panel 32 is hinged to the rear solid panel 33 along the lateral edge 34.

The cage too is preferably made of metal, but the whole device may be made of a synthetic plastic.

The disinfectant may be provided in solid form or again it may be a liquid which is supported within the cage upon a carrier such as cotton-wool.

The disinfectant permanently present in the inside of the mouthpiece slowly vapourizes and fills mouthpiece with vapour. When the disinfectant is exhausted or is losing its efficacy, the arm may be flexed to permit removal of the cage and insertion of a refill.

We claim:

1. A device for disinfecting a telephone mouthpiece comprising, in combination, a detachable cage for disinfectant formed from foraminated strip stock which is bent to a curve of a lesser concavity than that of the telephone mouthpiece, and an arm having a plug at one end effective to engage within and obturate a single peripheral aperture only of the diaphragm of the mouthpiece and elastically engaging at its other end with at least a portion of the surface of the cage whilst lying wholly within the confines of the mouthpiece.

2. A device for disinfecting a telephone mouthpiece comprising, in combination, a detachable cage for disinfectant formed from foraminated strip stock which is bent to a curve of a lesser concavity than that of the telephone mouthpiece, and an arm made from flexible strip steel of substantially rectangular cross section having one end formed as a pin of circular cross section adapted to fit within and obturate but a single peripheral aperture in the diaphragm of the mouthpiece and having a lip at its other end effective to engage elastically with the width of the cage whilst lying wholly within the confines of the mouthpiece.

3. A device for disinfecting a telephone mouthpiece as claimed in claim 1 in which a collar is provided on the pin to define the extent of its penetration into the aperture of the mouthpiece diaphragm.

4. A device for disinfecting a telephone mouthpiece comprising, in combination, a detachable cage for disinfectant formed from foraminated strip stock which is bent to a curve of a lesser concavity than that of the telephone mouthpiece and which is provided at least along one longitudinal edge with a crescent shaped flange, the curvature of the edge of which corresponds substantially to the curvature of the mouthpiece itself, and an arm having a plug at one end ef-

fective to engage within and obturate but a single peripheral aperture in the diaphragm of the mouthpiece and elastically engaging at its other end with at least a portion of the surface of the cage whilst lying wholly within the confines of the mouthpiece.

5. A device for disinfecting a telephone mouthpiece comprising, in combination, a detachable cage for disinfectant consisting of a solid rear panel bent to conform substantially to the curvature of the telephone mouthpiece, a foraminated front panel formed from strip stock hingedly connected to the solid rear panel at one lateral edge and bent to a curve of lesser concavity than that of the solid rear panel, and having longitudinally extending crescent shaped side flanges formed integral with the foraminated front panel and extending between the front and rear panels, and an arm having its one end formed as a pin of circular cross section effective to engage within and obturate but a single peripheral aperture in the mouthpiece diaphragm and its other end adapted to engage elastically with the foraminated front panel of the cage whilst lying wholly within the confines of the mouthpiece.

6. A device for disinfecting a telephone mouthpiece comprising, in combination, a detachable cage for disinfectant consisting of a front panel formed from foraminated strip stock which is bent to a curve of lesser concavity than that of the telephone mouthpiece, solid dependent crescent shaped flanges extending along each longitudinal edge of the said front panel and bent outwardly to provide guides extending the length of each crescent shaped flange, a solid rear panel which is bent to a curve of concavity substantially equal to that of the telephone mouthpiece, and inwardly directed channels formed integral with the solid rear panel adapted to engage with the guides on the side flanges of the front panel, and an arm having a pin at its inner end effective to engage within and obscure but a single peripheral aperture only of the mouthpiece diaphragm and elastically engaging at its outer end with at least a portion of the surface of the front panel of the cage whilst lying wholly within the confines of the mouthpiece.
